SOUND RECORDING SYSTEM

George P. Brubaker, Los Angeles, Calif., assignor
to Memovox, Incorporated, Beverly Hills, Calif.,
a corporation of Ohio

Application May 16, 1944, Serial No. 535,778

6 Claims. (Cl. 179—100.4)

1

This invention relates to a sound recording system, and more particularly to one in which a recording head co-operates with a moving record blank to form a sound track.

In such an arrangement, a source of motion is coupled to the record blank to move it at the desired speed past the recording head.

It is one of the objects of this invention to control the motor driving the record blank in such manner that the motor is deenergized when the sound impulses to be recorded have been discontinued.

It is another object of this invention to ensure that the record blank will not be stopped unless the silence persists for a short interval, of the order of a few seconds.

This invention possesses many other advantages, and has other objects which may be made more clearly apparent from a consideration of one embodiment of the invention. For this purpose there is shown a form in the drawing accompanying and forming part of the present specification. The form will now be described in detail, illustrating the general principles of the invention; but it is to be understood that this detailed description is not to be taken in a limiting sense, since the scope of this invention is best defined by the appended claims.

Referring to the drawing the single figure is a wiring diagram of a system incorporating the invention.

In this system there is shown a source of electrical impulses, such as microphone 1, that is in circuit with a source of direct current energy 2 and the primary coil 3 of a transformer 4.

The electrical impulses are thus transmitted to the secondary coil 5 of the transformer 4.

These electrical impulses, as is well understood, may be amplified by one or more amplifier stages 6, and are finally passed to a recording head 7. This recording head, while it might employ any one of numerous types of recorders, either photographic or mechanical, is shown in the present instance as including a stylus operating upon a record blank 8. This record blank 8 is shown as a disc appropriately supported upon a table 9 that is driven by a motor 10.

Motor 10 is shown in this instance as arranged in circuit with a source of direct current energy, such as the battery 11. It may also be shunted by a relatively large condenser 12 that reduces the fluctuations of current through the battery 11. The motor circuit is controlled by a relay 13 having a back contact 14. When the relay 13 is energized, as illustrated, the motor 10 is de-energized. When the relay 13 is de-energized, the back contact 14 completes the motor circuit through battery 11 and a control switch 15.

The relay 13 is so controlled that it drops its armature 16 when the impulses to be recorded

2

are being transmitted through the transformer 4 to the recording head 7; and the relay remains de-energized for an appreciable interval after suspension of the transmission of such impulses.

For this purpose relay 13 is shown as included in the output circuit of a thermionic vacuum tube 17. This tube 17 is shown as an electronic emission device utilizing a separately heated cathode 18, a control electrode or grid 19, an anode or plate 20, a screen grid 21, and a cathode heater 22. This heater 22 is shown as provided with heating current from battery 11.

The output circuit of the electronic emission device 17 thus includes the anode 20, relay 13, switch 15, and battery 11.

As is well understood, the amount of current permitted to flow in this circuit depends upon the potential difference between the cathode 18 and the grid 19. In the present instance, when there is substantially no potential difference between the input electrodes 18 and 19, then the relay 13 is operatively energized, and the motor 10 is inactive. When the impulses to be recorded are transmitted through the transformer 4, the current in the output circuit including relay 13 is materially reduced, and the armature 16 drops to close the energizing circuit for the motor 10. How this reduction is effected will now be described.

The secondary coil 5 of the transformer 4 is shown as connected at its opposite terminals to cathode 18 and the grid 19. A relatively large resistance 24 of the order of 20 megohms directly connects the cathode 18 and the grid 19.

While the system is inactive, there is no difference of potential across the secondary coil 5. Accordingly, the potential difference between the cathode 18 and the grid 19 is zero, since they are directly connected together through the resistance 24. The tube characteristic is such that, under these circumstances, an operative current flows through relay 13, and the motor circuit is therefore de-energized.

When impulses are being transmitted to secondary coil 5, an alternating electromotive force exists across the upper and lower terminals of secondary coil 5. This electromotive force affects the operation of the thermionic tube 17 in a way now to be described.

When the upper terminal of the secondary coil 5 is positive, sufficient potential difference exists between the cathode 18 and the grid 19 to produce a space current between these two electrodes. The battery 11 is so proportioned that the intensity of the signal impulses imposed upon the input side of the electronic emission device 17 is of the same order as the potential difference across the source 11. Furthermore, the potential difference impressed upon the plate 20 is quite low, or of the order of 20 to 30 volts.

Accordingly, the grid current flowing between cathode 18 and grid 19 during the positive half-cycle of the signaling impulse is relatively heavy, and the plate current is correspondingly reduced to a value that causes the relay 13 to drop its 5 armature 16. On the other hand, when the upper terminal of the coil 5 is negative, the negative potential thereby imposed upon the grid 19 stops any flow of output current, and thus de-energization of relay 13 is maintained.

Upon the suspension of the transmission of impulses, an interval must elapse before the potential on grid 19 returns to a value such as to re-energize the relay 13. By appropriate proportioning of condenser 23 and resistor 24, this interval can be chosen to be of the order of several seconds. This corresponds to the period of discharge of the condenser 23 through the resistance 24. Usually an interval of about six seconds is sufficient. When the interval is longer, the system returns to the position shown in the figure.

When, for example, the impulses being transmitted are set up by speaking into the microphone 1, any slight hesitation of the person using the system would not result in stopping of the 25 turntable 9.

Similarly, when the microphone circuit is first energized after a relatively long period of inactivity, the first few cycles of the voice currents 30 are capable of causing the relay 13 to be de-energized sufficiently to drop armature 16.

The inventor claims:

1. In a recording system utilizing a moving record blank: a recording head; means for imparting motion to the blank; means for transmitting impulses to be recorded to the head; and means for causing said motion imparting means to be active during periods when impulses are being transmitted, comprising an electronic emission device; an output circuit for said device and 40 controlling said means for imparting motion; and an input circuit for the device, said input circuit being subjected to the impulses and so proportioned that existence of said impulses causes reduction of the current in the output 45 circuit.

2. In a recording system utilizing a moving record blank: a recording head; means for imparting motion to the blank; means for transmitting impulses to be recorded to the head; and means for causing said motion imparting means to be active during periods when impulses are being transmitted, comprising an electronic emission device; an output circuit for said device and controlling said means for imparting motion; and an input circuit for the device, said input circuit being subjected to the impulses and so proportioned that existence of said impulses causes reduction of the current in the output circuit, and including a capacitance and a resistance 50 through which resistance the capacitance can be charged by aid of the impulses, and through which the capacitance can slowly discharge, to maintain said source of motion operative for limited periods between impulses.

3. In a recording system, a motor adapted to impart motion to a record blank, a recording head for co-operating with said blank, means for transmitting electrical impulses to be recorded to the recording head, an electronic tube having an input side and an output side, as well as electrodes associated with the input side and the outlet side, a circuit connecting the input side to the said means, and a device controlling the operation of the motor and connected to the out- 70

put side, said device, when operatively energized, causing the motor to be rendered inactive, said circuit including a resistance connecting the electrodes associated with the input side, for causing the flow of output current sufficient operatively to energize said device while no impulses are being transmitted, and a capacitance in the path of the impulses, the flow of current between the electrodes associated with the input side when impulses are transmitted being such that the output current is insufficient operatively to energize said device, and, when the impulses cease, the capacitance discharging through the resistance to maintain said energization of the device below operative value for a limited period.

4. In a system of the character described, an electronic emission device having a cathode, a control electrode, and an anode, means for transmitting impulses so as to impress an alternating potential difference between the cathode and control electrode, and an output circuit connecting the anode and cathode and including a source of potential difference so as to impress a potential on the anode which is positive with respect to the cathode, means operating in the absence of the impulses to maintain the potential difference between the cathode and control electrode at a value to cause the flow of current in the output circuit, the potential impressed upon the anode by said source being such, in relation to the characteristics of the electronic emission device and the intensity of the signaling impulses, that the resultant current flow in the output circuit is materially reduced while impulses are transmitted.

5. In a recording system utilizing a moving record blank: a recording head; means for imparting motion to the blank; means for transmitting impulses to be recorded to the head; and means for controlling said motion imparting means, including an electronic emission device having a cathode, grid, and anode; an input circuit connecting the cathode and grid and responding to the signaling impulses, said input circuit being so constructed and arranged that, when the grid becomes positive with respect to the cathode, a heavy grid current flows and reduces the flow of current between the cathode and anode, and, when the grid becomes negative, the flow of current from the cathode is blocked; and an output circuit connecting the anode and cathode and including a translating device operative to control the motion imparting means.

6. In a recording system utilizing a moving record blank: a recording head; means for imparting motion to the blank; means for transmitting impulses to be recorded to the head; and means for controlling said motion imparting means, including an electronic emission device having a cathode, grid, and anode; an input circuit connecting the cathode and grid and responding to the signaling impulses, said input circuit being so constructed and arranged that, when the grid becomes positive with respect to the cathode, a heavy grid current flows and reduces the flow of current between the cathode and anode, and, when the grid becomes negative, the flow of current from the cathode is blocked, said input circuit also including a capacitance in series with the grid, and a high resistance across the grid and cathode; and an output circuit connecting the anode and cathode and including a translating device operative to control the motion imparting means.

GEORGE P. BRUBAKER.
